DANIEL BLANCHARD, OF LOWELL, MASSACHUSETTS.

TENSION DEVICE FOR SHUTTLES.

1,026,298.

Specification of Letters Patent.

Patented May 14, 1912.

Application filed July 3, 1908. Serial No. 441,770.

To all whom it may concern:

Be it known that I, DANIEL BLANCHARD, a citizen of the United States, residing at Lowell, in the county of Middlesex and State of Massachusetts, have invented certain new and useful Improvements in Tension Devices for Shuttles, of which the following is a specification.

This invention relates to tension devices for loom shuttles. Its object is to exert sufficient tension upon the filling yarn from the bobbin or cop in the shuttle to prevent it from running out too rapidly through the shuttle eye thereby becoming tangled and causing uneven cloth.

In the drawings Figure 1 is a top view of the device in place; Fig. 2 is a sectional view from the side; Fig. 3 is a top view with the addition of an adjusting screw. Fig. 4 shows a modification of the device. Fig. 5 is an enlarged view from the front showing the effect of the yarn passing between the spring wings. Fig. 6 shows the blank from which my device is formed. Fig. 7 shows another modification and the manner of attaching it to the shuttle.

A is the shuttle, B is the bobbin and C is the filling yarn.

D is the shuttle eye and E is the recess to receive the bobbin.

My device is made entirely of thin sheet metal and on that account is so light that it does not overbalance or disturb the equilibrium of the shuttle. Referring to Fig. 6 the device is formed of one piece of metal which is cut at one end to form blades 11 and is cut in the center to leave a tang 12 pierced at 13 to receive a screw.

The wings 15, 15 at the end of which are lips 16 are first bent up and forward into the curved shape shown in Figs. 1 and 3. Sides 14, 14 are then bent up at right angles to blades 11, 11 and to the flat portion 10 which forms the base plate to such a point that lips 16 about touch each other. Lips 16, 16 are preferably curved to present convex surfaces to each other. Tang 12 is bent down to fit shoulder 30 to which it is to be screwed. Tang 12 and blades 11, 11 fit the woodwork and steady and hold the device stiffly in place. Wings 15, 15 preferably have their top edges beveled as shown in Fig. 5 to aid the yarn to slide downward into place. The lips 16 project downward and between and beyond blades 11. A de-

pression 20 must be made in the shuttle to receive them.

Most shuttles are cut with a shoulder 30 which rises from recess E and forms a platform 31 upon which felt or other retarding device is tacked for the same purpose as my device. Preferably base plate 10 and blades 11 rest on this platform 31 and tang 12 fits over shoulder 30 to which it is fastened by a screw 32. To further hold it in place and to prevent the yarn from being caught, I cut away the shuttle at 33, 33 to receive the ears 17 formed by doubling wings 15 over on sides 14.

The wing 15 and the side 14 are so cut that when bent into position they will slope downward toward the shuttle eye D as shown in Fig. 2. It will readily be seen that the yarn C passing between the lips 16 will be retarded to a greater or less degree according to the strength of the spring in wings 15. The tension may be increased or decreased by pinching these wings closely together or pressing them apart.

A more accurate method of adjustment is shown in Fig. 3 wherein I insert the screw 40 through the side of the shuttle so as to bear against one of the wings 15. By screwing in or out this adjustment screw 40, the tension can be increased or diminished. The depression 41 is made in the side of the shuttle to receive screw 40. To reduce the weight, on some shuttles I can cut off the tang 12 and do away with screw 32 as shown in Fig. 4.

In Fig. 4 depressions 42 are cut on the inside of the shuttle and the ears 18 are pressed into them. The blades are made longer and they are pointed so that they form prongs 43 which can be driven longitudinally into the shuttle on each side of the shuttle eye D. For some types of shuttles, it is better to have the pointed prongs 44 bent downward and driven in vertically as shown in Fig. 5. In this type of device, it is better to retain tang 12 as it extends downward and prevents the yarn from catching under the device, if it curls up or becomes loose. Instead of being made all in one piece as described the wings 45 may be riveted by rivets 46 to the sides 14 as shown in Fig. 4.

Fig. 5 shows how the yarn C after sliding into place between the lips 16, on account of the fact that the spring at the bot-

tom is less than at the top, forces the top of the lips inward and the bottom outward thereby tending to hold itself in place.

The principal advantages of my device are its lightness whereby the shuttle is not overbalanced, its simplicity of construction, the fact that it threads itself and does not interfere with the threading of the shuttle eye, and the fact that the yarn will not catch upon it.

10 What I claim as my invention and desire to cover by Letters Patent is:—

1. A tension device for shuttles which comprises a base plate, blades which project therefrom, sides, which rise vertically therefrom, wings attached thereto which slant downward between said sides toward the shuttle eye and are formed with lips which pass below and between said blades.

15 2. A tension device for shuttles which comprises a base plate, blades which project therefrom, sides which rise vertically there-

from, wings attached thereto which slant downward between said sides toward the shuttle eye and are formed with lips which 25 pass below and between said blades and means for attaching the base plate to the shuttle.

3. A tension device for shuttles which comprises a base plate, blades, pointed 30 prongs which project therefrom and enter the wood of the shuttle, sides which rise vertically therefrom, wings attached thereto which slant downward between said sides toward the shuttle eye and are formed with 35 lips which pass below and between said blades as described.

In testimony whereof I affix my signature in presence of two witnesses.

DANIEL BLANCHARD.
